DESIGN FOR AN ICE SKATE

Samuel G. McCullough, Narragansett, R. I.

Application February 9, 1943, Serial No. 109,509

Term of patent 14 years

To all whom it may concern:

Be it known that I, Samuel G. McCullough, a citizen of the United States, residing at Narragansett, in the county of Washington and State of Rhode Island, have invented a new, original, and ornamental Design for an Ice Skate, of which the following is a specification, reference being had to the accompanying drawing, forming part thereof.

Figure 1 is a side elevational view of an ice skate showing my new design.

Figure 2 is a top plan view.

Figure 3 is an end elevational view looking at the forward end of the skate.

I claim:

The ornamental design for an ice skate, as shown.

SAMUEL G. McCULLOUGH.
